D10-9. OR D 862 EX

Dec. 862

Charles Chinnock of New York, N.Y.
Letters Patent No. 862. Dated Jan'y 6. 1837

The schedule referred to in these Letters Patent and
making part of the same.

To all whom it may concern:

Is it known that ³
Charles Chinnock, of the City, County and State
of New York, have invented or produced a new and
original design for Clock Case Fronts, and do now
by declare that the following is a full, clear and ex-
act description of the same, reference being had to the
enlarged drawings making a part of this specifica-
tion, in which:

Fig: 1. is a face view of a clock case front
showing my design.

Fig: 2. is a transverse vertical section of
do. & 2. fig: 1. showing the plane of section.

A. represents the circular opening in the
case front, which front exposes the dial of the clock.

B. is the opening which exposes the funda-
mental bob.

C,C. are projecting scrolls, one at each
side of the case front and in line with the upper
part of the opening A. D. is a trefoil ornament at
the upper front of the case front.

E. is a wreath formed of a grape vine,
G. being the stalk, F the leaves and H the fruit, the
wreath being at each side of the case front, and
at the top and just above the base of the case front,
as clearly shown in fig: 1, the wreath forming a bor-
der or edging to the whole of the case front except its
base.

What I claim as new and desire to es-
tablish by Letters Patent, is

The configuration of the
wreath and projecting scrolls, as described, the
